(57) **CLAIM**

I claim the ornamental design for a bicycle wheel rim, as shown and described.

DESCRIPTION

FIG. 1 is a perspective view of the bicycle wheel rim showing my new design;

FIG. 2 is a front view of the rim, the rear view of the rim being the same one;

FIG. 3 is a left view of the rim, the right view of the rim being the same one;

FIG. 4 is a top plan view of the rim, the bottom plan view of the rim being the same one; and,

FIG. 5 is an enlarged cross-sectional view of the rim thereof, taken along line 5-5 in FIG. 2.

The broken line showing of the interior wall of the bicycle wheel rim is for the purposes of illustration and forms no part of the claimed design.
